DISHWASHING MACHINE

Ulysses S. G. Welsh, New York, N. Y.

Application January 21, 1937, Serial No. 121,484

1 Claim. (Cl. 141—9)

This invention relates to dishwashing machines, and has for an object to provide an improved construction over the construction shown in my prior Patent No. 1,457,240 issued May 29, 5 1923.

Another object of the invention is to provide a dishwashing machine wherein means are provided which will project the washing water or other solution both laterally and substantially 10 vertically.

A further object of the invention is to provide a washing machine with a closed casing and with means for causing the water or other washing solution to strike the dishes or other articles being washed from beneath, on each side, and from the top and bottom.

An additional object, more specifically, is to provide a dishwashing machine having a structure in the form of a well near the bottom 15 accommodated impelling blades for directing water upwardly against the sides of the casing together with means carried by the sides of the casing for causing some of the water or washing solution to move laterally while other parts of 20 the water move in a spray upwardly.

In the accompanying drawings:

Fig. 1 is a longitudinal vertical sectional view through a washing machine disclosing an embodiment of the invention, the section being 30 taken approximately on the line 1—1 of Fig. 2;

Fig. 2 is a horizontal sectional view through Fig. 1 approximately on the line 2—2;

Fig. 3 is a top plan view of a projecting element disclosing certain features of the invention;

Fig. 4 is a side elevation of the element shown in Fig. 3;

Fig. 5 is an edge view of the structure shown in Fig. 4;

Fig. 6 is a sectional view through Fig. 3 approximately on the line 6—6;

Fig. 7 is a fragmentary sectional view through Fig. 5 approximately on the line 5—5.

Referring to the accompanying drawings by numerals, 1 indicates a casing which may be 45 metal, glass or other material and which is preferably cylindrical. A ring 2 is carried at the top of the casing 1 and secured thereto by welding or other desired means, said ring being of metal or other desired material. Preferably 50 ring 2 is made from metal and is provided with an annular offset 3 for receiving the depending part 4 of a cover 5 which may be made of metal, glass or other material. A hinge 6 of any desired structure connects the cover 5 with ring 2 55 while the catch or clamp 7 provides means for

disengageably locking the cover in its closed position. This cover is provided with an opening 8 having a closure 9. The material forming the opening 8 is provided with a number of small vents 10 to permit air or gas to readily escape. 5

The cover 5 is provided with annular raised outer portions 11 and 12 whereby curved walls 13 are provided, said walls being annular. This structure is formed by depressing the central part 14 whereby an annular groove substantially arc-shaped in cross section is presented. This formation is desirable as hereinafter fully described whereby water passing upwardly along the inner surface of the casing 1 may move off as indicated by arrows 15 or may pass around and be deflected 10 as indicated by arrow 16. In this way water or other washing solution moving in this direction will be projected on top of articles carried by the respective upper and lower containers 17 and 18. It will be understood that the dishes or other articles being washed are to be supported by these containers. 15

At the lower part of the casing 1 there is provided what may be termed a bottom member 20 formed with a shoulder 19 on which the casing 1 25 rests. If desired the casing could be welded or otherwise rigidly secured to the bottom member 20 or the annular extension 21. Any desired number of legs 22 are bolted or otherwise rigidly secured to the depending part 23 of bottom 20. 30 This provides a sturdy, strong and rigid structure for supporting the upper part of the machine. The bottom 20 is annular and presents an inverted cone-shaped well 24 in which operates the impeller 25, which impeller is provided 35 with two or more impelling blades 26 and a tubular body 27 having a closed top 28 which rests on a suitable journal member 29 carried in the protecting casing 30 which may be formed integral with the tubular depending extension 31 40 of bottom 20. Preferably member 29 is supported by suitable ballbearings although it could be supported by other forms of bearings. 45

Member 29 is provided with a restricted extension 32 carrying a worm wheel 33 meshing continually with the worm 34 connected to shaft 35. Shaft 35 is connected through a clutch 36 to the moving parts of the power member 37. Power member 37 may be an electric motor or other power member, while the clutch 36 may be of any desired kind and may be such that it can be disengaged manually at any time, although ordinarily the machine is started and stopped by turning on and off current to the motor 37. The speed of rotation of motor 37 is such that the 50 55

impellers 26 will rotate at a desired speed which will cause the water to be projected upwardly and outwardly whereby most of the water will strike the cylinder or casing 1 at or slightly above the 5 wire container 18. The water or other washing solution is directed upwardly and outwardly in a whirling motion so that the liquid will pass upwardly and also in a spiral around the casing 1. Part of the water will be deflected from the 10 casing by the three deflectors 38, part will be deflected and projected by the projecting members 39, and part will pass upwardly and move substantially as indicated by the various arrows 15 and 16. In this way the washing solution or 15 water is directed against the sides and lower surface of all the dishes or other articles carried by the containers 17 and 18 and also directed against the top and sides of the dishes carried by the respective containers.

20 As indicated in Fig. 2, the deflectors 38 deflect in a more or less radial direction as indicated by the various arrows 40. The water is directed more or less radially inwardly and in a more or less horizontal direction, although some of the water will move slightly upwardly and other portions of the water slightly downwardly whereby an almost horizontal zone of sprayed water will be presented which eventually will drop downwardly in curved lines and strike the various dishes in the container 18. The deflecting surface 13 performs more or less the same function for the dishes in the upper container 17. While this is taking place a desired proportion of water or other washing solution is deflected or in a certain sense projected upwardly in an ever widening spray. As indicated in Fig. 2, each spray covers a little over one-third of the surface as indicated by the arrows 41 and 42. In this way practically all of the undersurface of the container 17 and 40 any articles thereon will be subjected to some of the sprayed water or projected water from the projectors 39.

As has been found by experience, three deflectors 38 are satisfactory and in fact most desirable, but also it has been found that the three projectors 39 produce the most satisfactory results, although if desired a larger number of these members might be used or, under some circumstances, a less number. If the washing machine is very small, probably a less number would be satisfactory, whereas if the machine were extra large, more of these members might be desirable. Whether more or less of these members are used, they all function in the same way to cause the water or washing solution to be projected rather forcefully over the entire surface of each article in each of the containers. Where cups and more or less hollow containers are to be washed, this is very desirable as it causes a thorough cleaning action interiorly as well as exteriorly of the article.

60 The various deflectors 38 present arc-shaped surfaces as shown particularly in Fig. 2 and are comparatively short in length as indicated in Fig. 1 so that the length of these are usually about the same as the height of the upper container 17, although this is not essential. The same may be said of the projectors 39. In addition, the projectors 39 have been shown more or less in detail 65 in Figs. 3 to 7 inclusive. Referring particularly to these figures, it will be observed that each of these projectors is provided with a base 43 which is secured by screws or otherwise rigidly secured to the casing 1 and which merge integrally into a 70 coiled formation 44 which flares from the bottom

75 to the top. This flare is uniform from the bottom to the line 45 as shown in Fig. 6, and then the flare increases on the side or surface 46 and decreases on the side or surface 41. This causes a slight deflection or change of direction of the moving water so that it will be distributed more evenly toward the center of the casing 1. It will be noted that the surface 46 is nearest the center of the casing. It will also be noted from Fig. 4 particularly that the coiled extension 44 is cut 10 away at 48 so as to permit an easier and greater change of direction of the moving water. These features are desirable because the projectors are at the sides of the casing and consequently it is 15 desirable to project the water not only upwardly but more or less laterally towards the center of the casing in order to secure the distribution indicated by the arrows 41 and 42.

When it is desired to wash a given batch of 20 dishes or several batches of dishes, a desired quantity of water, soap or other detergent is deposited in the casing. This washing solution may extend upwardly to the bottom of the container 18 or slightly above the same. The cover 5 is swung off to one side and then the filled container 18 inserted so that the supporting legs 49 thereof rest on the shoulder 19. The upper container 17 is then filled and inserted so that the lower part thereof will rest on the deflectors or deflecting elements 38. It will be understood 25 that preferably the containers 17 and 18 are formed as a metal wire structure with sufficient cross members to receive and support dishes or other articles of various sizes. The washing solution may be inserted before or after the filled 30 containers, said solution being preferably inserted through the inlet pipe 50 which may, if desired, be provided with a valve. The bottom 20 is provided preferably with an integral extension 51 which is hollow and to which is secured the drain pipe 52 whereby the liquid in the container may be drained off at any time. At 35 any desired point along its length pipe 52 may be provided with a valve which is normally closed but which must be opened to drain the liquid from the casing 1.

After the washing liquid has been inserted and the containers with their dishes also inserted, the cover 5 is closed and clamped in closed position by the clamp or lock 7. Current is then turned 40 on to the electric motor 31 and the machine will immediately begin to function. The machine may be allowed to function any desired length of time according to the condition of the dishes or other articles being washed. Ordinary dishes 45 may be properly washed in from one to three minutes although it will not injure any parts to allow the machine to function for a much longer time or even to function continuously. It is of course understood that the motor 31 must be stopped before the cleaned or washed dishes may be removed out of the top of the casing. Ordinarily the containers with their cleaned dishes are 50 removed and new containers with dirty dishes immediately inserted and the cover 5 closed. The motor is again turned on so as to repeat the 55 washing operation. Unless the dishes are extremely dirty, one charge of washing liquid will clean several batches of dishes. Ordinary water and soap are used although other solutions might be used if desired. Also if desired the dishes 60 may be subjected to a spray of fresh water after having been removed from the machine so that they will be rinsed.

I claim:

A dish washing machine comprising a casing having a cone-shaped base with a tubular side structure rising from the periphery of the base, 5 a closure for the top of said tubular side structure, an impeller structure arranged in said base and terminating near said tubular side structure for forcing liquid in a film-like form in an upward direction against said tubular side structure, 10 said closure at the top coating with said tubular side structure to cause said liquid to be deflected downwardly with some appreciable force, deflecting means carried by said tubular side structure intermediate its length for deflecting 15 a portion of said liquid radially laterally and

downwardly, and projecting means carried by said tubular side structure positioned below said deflecting means for projecting a portion of the liquid from said tubular side structure upwardly in a substantially cone-shaped formation with the axis of the cone at an angle to the vertical when the axis of the tubular side structure is vertical, and a pair of containers arranged within said casing for supporting articles to be washed, one of said containers being positioned in the path of the liquid deflected by said closure and projected by said projecting means and the other in the path of liquid deflected by said closure and deflecting means. 5 10 15
